UNITED STATES PATENT OFFICE.

JAMES A. DONNELLY, OF BROOKLYN, NEW YORK.

STEAM HEATING APPARATUS.

SPECIFICATION forming part of Letters Patent No. 670,893, dated March 26, 1901.

Application filed May 14, 1900. Serial No. 16,548. (No model.)

To all whom it may concern:

Be it known that I, JAMES A. DONNELLY, of the borough of Brooklyn, Kings county, State of New York, have invented an Improvement 5 in Steam Heating Apparatus, of which the following is a specification.

My invention relates to steam heating apparatus, and is fully set forth in the following specification and shown in the accompanying 10 drawings.

It is an object of my invention to render a steam-heating system automatic in the regulation of the outlet-valves which control the discharge of the air and water of condensation from the heaters, coils, or other radiating 15 devices.

In carrying out my invention I employ a valve-actuating device operated by the difference in pressure in the return or outlet side 20 and in the radiator or inlet side and means controlled by the conditions on the inlet side, such as the pressure or the presence of steam or water, to control the differential pressure acting on the valve-actuating device. Thus 25 while the operation of the valve is effected by means of the differential pressure that differential pressure and the operation of the valve are regulated and controlled by the conditions existing on the inlet side, so that the 30 valve passage-way will be opened or closed to a greater or less extent, as the existing conditions on the inlet side may require, and a very regular and certain operation is obtained.

In the preferred embodiment of my invention, as shown in the drawings, the means for actuating the valve consist of a pressure-motor communicating with the return or outlet side. By employing as the pressure-motor a flexible diaphragm having one side subjected to the pressure or conditions on the inlet side communicating with the radiating devices and the other side subjected to the 40 pressure or conditions on the outlet side communicating with the return I am able to control the operation of the outlet-valve operated by said diaphragm by the relation between the pressures in the radiator and return. If the outlet-valves remain constantly open to an extent necessary to effect the discharge of the water of condensation, there is 45 liability of "short-circuiting" and waste of steam, and this is particularly the case in

those systems in which a partial vacuum or lower pressure is created in the returns for the purpose of drawing out the air and water. 55

It is also an object of my invention to render the valves automatic, so that they will open or close, according to the conditions existing in the radiating devices or returns at which they are located, thus enabling the water of 60 condensation and air to be fully discharged, but preventing the waste of steam. This result has been accomplished heretofore by the use of thermostatic valves and steam-traps, which remain open to permit the air and water to escape, but close to the passage of steam; but it is an object of my invention to accomplish this automatic regulation without the use of thermostatic devices for that 65 purpose. 70

The preferred means for controlling the operation of the pressure-motor consist of a float controlled by the water of condensation on the inlet side and controlling a vent in the pressure-motor, by which the differential pressure and the operation of the motor are regulated. 75

Figure 1 is a vertical sectional view of a valve device embodying my invention. Fig. 2 is a similar view illustrating a different 80 form. Fig. 3 is an enlarged vertical sectional view of part of the valve device of the character shown in Fig. 2, illustrating a modification. Fig. 4 is a diagrammatic view of a steam heating apparatus embodying the invention, and Fig. 5 is a vertical sectional view of a valve device embodying a different 85 form.

A is any source of steam-supply, such as the exhaust-pipe of an engine. 90

B B are radiating devices—such as heaters, coils, &c.—communicating with the exhaust or source of steam-supply A in the usual manner.

C C are the returns from the radiating 95 devices.

D is a vacuum-pump or other exhausting apparatus connected with the returns and adapted to create a partial vacuum or lower pressure therein. 100

E E are the automatic valves located in the outlets of the radiating devices or at any other suitable place in the return portion of the system between the outlets of the radiat-

ing devices and the pump. I have shown three forms of these automatic valve devices E, and other modifications and forms may be used without departing from the invention, 5 provided the essential feature of the operation of the valve through means actuated by the differential pressure in the outlet and inlet when controlled by means governed by the conditions existing on the inlet side is 10 employed.

F is the valve-body having the usual inlet *a* and outlet *b*, with the valve passage-way or thoroughfare *c*, controlled by the valve-piece *d*. The valve-piece *d* is connected with 15 and controlled by the motor *e*, which, as stated, is operated by the differential pressure in the outlet and inlet sides. As shown, the motor consists of a flexible diaphragm clamped between the valve-bonnet *f* and a cap *g* and 20 forming a closed motor-chamber *h* in the top of the valve device below the cap. The valve-piece *d* is connected with the motor *e* by a tube *i*, extending through the diaphragm and valve-piece, respectively, and provided with 25 a small duct or passage-way *j*, which forms a communication between the motor-chamber *h* and the return or outlet side *b* of the valve device. A small spring *k* between the diaphragm and the cap may be used to hold the 30 diaphragm in a normally-lowered position, with the valve-piece *d* closed upon its seat, and the tension of this spring may be adjusted by a nut *g'* on the cap. The spring may, 35 however, be omitted.

35 The partial vacuum or lower pressure in the outlet or return *b* will extend through the duct *j* into the motor-chamber *h*.

To control the operation of the motor by the conditions existing on the inlet side, I provide a vent *l*, leading into the motor-chamber *h* from the inlet side, through which the air may be drawn out from the radiator while the valve *d* is closed. This vent is of larger area than the duct *j*, so that the air will not 45 be exhausted from the motor-chamber *h* faster than it can enter through the vent. It consequently follows that while the vent *l* is open it forms an intercommunication between the opposite sides of the diaphragm, and the pressures on the opposite sides will be equal and 50 there will be no movement of the diaphragm or valve *d*. When, however, the vent *l* is closed and the pressure in the chamber *h* is reduced, the pressure on the inlet side will lift the diaphragm and open the valve. This vent *l* may 55 be controlled by the conditions existing on the inlet side; but as the accumulation of water of condensation is the condition which is of chief importance I prefer to control the 60 vent *l* automatically by the water of condensation. For this purpose I employ a float *m*, arranged within the inlet side and adapted, when acted upon by the accumulation of water in the valve, to close the vent. In the 65 construction shown in Fig. 1 the float *m* rests upon the valve-piece and embraces the tube *i*. It carries a valve *n*, adapted when the

float is lifted to close upon the vent *l*. A pin *o*, projecting from the valve *n*, serves to hold the float in alinement and guide the valve 70 and also to keep the vent free and unobstructed by particles of foreign matter.

In the construction shown in Fig. 2 the float *m* is arranged in the upper part of the valve-body, and instead of the pin-valve *n* it carries a valve-plate *n'*, adapted to close upon the vent. 75

In the construction shown in Fig. 5 a cup-shaped float *m'* is employed, which is adapted to float in the water of condensation. This 80 float carries a pin *p*, which extends through the vent *l* and supports a valve *n''* within the chamber *h*. When the float *m'* falls, the pin *p* permits the valve *n''* to close on the vent *l*. The float *m'* is of annular form, loosely embracing the tube *i*, and a tube *r*, carried by the diaphragm *e*, extends down into the float nearly to the bottom. *s* is an annular rib about the outlet *c*, forming a support for the float *m'* when it sinks. The float *m'* being 90 partially filled with water floats in the body of water in the valve-body, with the valve *n''* raised and the vent open. When, however, an excess of water accumulates and passes into the open top of the float, the float will 95 sink upon the rib *s* and close the vent *l*. The valve *d* is then opened; but as the seating of the float upon the rib *s* will close the direct passage-way the water will be drawn out through the float and will pass from the outlet into the float and thence up between the tube *r* and the inner wall of the float and down through the inner passage-way about the tube to the outlet *c* until the float is emptied to an extent sufficient to enable it to rise again and 100 open the vent, when the diaphragm will instantly close the valve *d*.

A tube *t* may be arranged about the float in each construction, extending down to nearly the bottom of the valve-body to direct the 110 water of condensation toward the bottom and to cause it to rise upward.

While the vent *l* is open and the valve *d* is closed the air will be drawn out of the radiators through the small thoroughfare afforded 115 by the duct *j* and vent *l*, and the valve *d* will be opened only when there is an accumulation of water of condensation. This small thoroughfare, while sufficient for the discharge of the air, will not permit the escape 120 of any appreciable volumes of steam, as would occur if the large thoroughfare afforded by the valve *d* were open. There will consequently be no short-circuiting or waste of steam, and the system will be entirely automatic in its 125 operation.

To control the size of the suction or discharge passage-way formed by the duct *j*, the top of the tube *i* may be provided with a small cap *j'*, having a small orifice *j''*, as shown in 130 Figs. 2 and 3.

If desired, the air passage-way formed by the duct *j* and vent *l* may be controlled thermostatically—i. e., by means of a thermostat

controlled by the temperature of the steam. In Fig. 3 I have shown such a construction in which a small thermostatic expanding piece *w* is arranged within the duct *j* and is adapted, 5 when subjected to the temperature of steam, to expand, and thus restrict the thoroughfare through the orifice *j'*.

Besides the particular devices shown other 10 means may be employed for controlling the operation of the motor *e* and valve *d* under the action of the partial vacuum or conditions existing on the outlet side or return.

While I have shown my invention embodied 15 in a system in which a partial vacuum or lower pressure is created in the returns by means of an exhausting device connected therewith, the invention may also be embodied in a pressure system in which such exhausting device is not employed. In either 20 case the operation of the valve-actuating motor will be operated by the difference in pressure in the returns and in the inlet side or radiator, while that difference in pressure will be controlled by the devices controlled 25 by the conditions existing in the inlet side.

What I claim as new, and desire to secure by Letters Patent, is as follows:

1. In a steam heating apparatus, the combination of a radiating device, a return for 30 the air and water of condensation leading therefrom, a valve interposed between the outlet of the radiating device and the return, a pressure-motor for operating said valve interposed between the valve and the outlet of 35 the radiating device and having its opposite sides acted upon respectively by the pressure in the radiator-outlet and in the return, and means automatically controlled by the conditions in the inlet side of said valve to control 40 the differential pressure acting on the motor and the operation of the valve.

2. In an automatic valve device for steam-heating systems, the combination of a valve-body having a valve-seat, a valve-piece to 45 control said valve-seat, a pressure-motor controlling said valve-piece located within the said valve-body between the inlet and valve-seat, and having one side subjected to the pressure on the inlet side of the valve-body, 50 and the other side subjected to the pressure on the outlet side beyond the valve-seat, and means controlled by the conditions on the inlet side of the valve to automatically control the pressure acting on the valve-motor from 55 the side in communication with the outlet side of the valve-body beyond the valve-seat, whereby the differential pressure acting upon said pressure-motor to operate the valve-piece is controlled by the conditions existing 60 on the inlet side of the valve-body.

3. In an automatic valve device for steam-heating systems, the combination of a valve-body having a thoroughfare, a valve-piece to control said thoroughfare, a pressure-motor 65 for controlling said valve-piece having communication on one side with the inlet side of the valve-body and on the other side with the

outlet side beyond the thoroughfare and an intercommunication between said communications, and mechanical means controlled by 70 the conditions existing on the inlet side of the valve-body for closing said intercommunication to establish a differential pressure acting on said pressure-motor.

4. In a steam heating apparatus, the combination with a radiating device, a return for 75 the air and water of condensation leading therefrom, a valve between the outlet of the radiating device and the return, a pressure-motor for controlling said valve operated by 80 the difference in the pressure in the radiating device and the return, and provided with a normally open controlling-vent forming a communication between the inlet and outlet sides of said valve, and means controlled by 85 the conditions on the inlet side of said valve to control said vent and the operation of the pressure-motor controlled thereby.

5. In a steam heating apparatus, the combination with a radiating device, a return for 90 the air and water of condensation leading therefrom, a valve between the outlet of the radiating device and the return, a pressure-motor for controlling said valve communicating with the pressure in the return and provided with a normally open vent forming a communication between the inlet and outlet sides of said valve, and means controlled by 95 the conditions on the inlet side of said valve to control said vent and the operation of the pressure-motor and valve under the action of the pressure in the return.

6. In a steam heating apparatus, the combination with a radiating device, a return for 100 the air and water of condensation leading therefrom, a valve between the outlet of the radiating device and the return, a pressure-motor for controlling said valve communicating with the pressure in the return and provided with a normally open vent forming a 105 communication between the inlet and outlet sides of said valve, and a float controlled by the water of condensation on the inlet side of said valve to control said vent.

7. In an automatic valve device for steam-heating systems, the combination of a valve-body having a thoroughfare, a valve-piece to control said thoroughfare, a pressure-motor for controlling said valve-piece having its opposite sides directly and constantly exposed 120 to the pressure on the inlet and outlet sides of the valve-body respectively and adapted to be operated by the difference in said pressures, and means controlled by the conditions on the inlet side to automatically control the 125 difference in said pressures and the operation of the motor and valve-piece thereby.

8. In an automatic valve device for steam-heating systems, the combination of a valve-body having a thoroughfare, a valve-piece to 130 control said thoroughfare, a pressure-motor for controlling said valve-piece communicating with the valve-body on the outlet side beyond the thoroughfare, and provided with a

normally open vent forming a communication with the inlet side of said valve-body, and means controlled by the conditions on the inlet side to control said vent and the operation 5 of the pressure-motor under the difference in pressure on the outlet and inlet sides.

9. In an automatic valve device for steam-heating systems, the combination of a valve-body having a thoroughfare, a valve-piece to 10 control said thoroughfare, a pressure-motor for controlling said valve-piece communicating with the valve-body on the outlet side beyond the thoroughfare, and provided with a normally open vent forming a communication 15 with the inlet side of said valve-body, and a float located on the inlet side and adapted to control said vent.

10. In an automatic valve device for steam-heating systems, the combination of a valve- 20 body having a thoroughfare, a valve-piece to control said thoroughfare, a pressure-motor for controlling said valve-piece having communication on one side with the inlet side of the valve-body and on the other side with the 25 outlet side beyond the thoroughfare and an intercommunication between said communications, and a float controlled by the water of condensation on the inlet side of the valve- 30 body for closing said intercommunication to establish a differential pressure acting upon said pressure-motor.

11. In an automatic valve device for steam heating apparatus, the combination with the valve - piece, of a pressure - actuated dia- 35 phragm for operating said valve-piece, a duct leading through said diaphragm from the outlet side of the valve device, whereby the operation of said diaphragm and valve-piece is controlled by the relative pressure or partial 40 vacuum on the outlet side, and means controlled by the conditions on the inlet side of said valve device to control the relative pressure or partial vacuum acting on the side of said diaphragm in communication with the 45 outlet side of the valve device.

12. In an automatic valve device for steam heating apparatus, the combination with the valve - piece, of a pressure - actuated dia- 50 phragm for operating said valve-piece, a duct leading through said diaphragm from the outlet side of the valve device, whereby the operation of said diaphragm and valve-piece is controlled by the relative pressure or partial 55 vacuum on the outlet side, said diaphragm being provided with a vent forming a normally open communication with the inlet side of the valve device, and means controlled by the conditions on the inlet side to control said vent.

60 13. In an automatic valve device for steam heating apparatus, the combination with the valve - piece, of a pressure - actuated dia- phragm for operating said valve-piece, a duct leading through said diaphragm from the outlet side of the valve device, said diaphragm being provided with a vent forming a normally open communication with the inlet side

of the valve device, and a float in the inlet side to control said vent.

14. In an automatic valve device for steam-heating systems, the combination of a valve- 70 body having a thoroughfare, a valve-piece to control said thoroughfare, a pressure-motor for controlling said valve-piece having communication on one side with the inlet side of the valve-body and on the other side with the outlet side beyond the thoroughfare and an intercommunication between said communications, mechanical means controlled by the conditions existing on the inlet side of the 80 valve-body for closing said intercommunication to establish a differential pressure acting on said pressure-motor, and a thermostat for thermostatically controlling the area of said intercommunication. 85

15. In an automatic valve device for steam heating apparatus, the combination of a valve- 90 body having a thoroughfare, a valve-piece controlling said thoroughfare, a pressure-actuated diaphragm for controlling said valve- piece, a tube connecting said diaphragm and valve-piece and forming a communication between the outlet side of the valve device and the space adjacent to the diaphragm, said diaphragm being provided with a normally 95 open vent forming a communication through the diaphragm with the inlet side of the valve device, and means controlled by the conditions on the inlet side for controlling said vent. 100

16. In an automatic valve device for steam heating apparatus, the combination of a valve- 105 body having a thoroughfare, a valve - piece controlling said thoroughfare, a pressure-actuated diaphragm for controlling said valve- piece, a tube connecting said diaphragm and valve-piece and forming a communication between the outlet side of the valve device and the space adjacent to the diaphragm, said diaphragm being provided with a normally 110 open vent forming a communication through said diaphragm with the inlet side of the valve device, and a float on the inlet side of the valve device for controlling said vent. 115

17. In an automatic valve device for steam heating apparatus, the combination of a valve- 120 body, a valve - piece to control the passage through said valve-body, a flexible diaphragm in the upper part of the valve-body forming a closed chamber, a connection between said diaphragm and valve-piece, a duct between the chamber formed by said diaphragm and the outlet side of the valve-body beyond the valve - piece, whereby the operation of said diaphragm and valve is controlled by the difference in pressure on the inlet and outlet sides, and means within the valve-body controlled by the conditions on the inlet side to control the differential pressure and the operation of said diaphragm and valve-piece. 125

18. In an automatic valve device for steam heating apparatus, the combination of a valve- 130 body, a valve - piece to control the passage through said valve-body, a flexible diaphragm

in the upper part of the valve-body forming a closed chamber and provided with a normally open vent forming a communication through said diaphragm with the inlet side of the valve-body, a tube connecting said diaphragm and valve-piece and forming a communication between the closed chamber above the diaphragm and the outlet side of the valve-body beyond said valve-piece, and

a float within the valve-body controlling said vent.

In testimony of which invention I have hereunto set my hand.

JAMES A. DONNELLY.
